UNITED STATES PATENT OFFICE.

JOHN R. NEIDIG, OF OILMONT, MONTANA.

MANICURING IMPLEMENT.

Application filed May 2, 1928. Serial No. 274,566.

This invention relates to manicuring implements, and the primary object thereof is to provide a three-in-one implement which will take the place of the individual wad of 5 cotton, rosewood stick, and cuticle bottle, and which will yet be compact in form and simple in construction.

Another object of the invention is to provide a device of this character which, while 10 serving the purpose of the usual orangewood or rosewood stick for pushing back the cuticle and removing foreign accumulations from the inner and outer margins of the nail, also is equipped with means for supplying in 15 regulated quantities to the tip liquid medicaments desired to be used in connection with the treatment of the nails.

Still another object of the invention is to provide simple and improved means for 20 controlling the flow of the liquid medicament to the tip.

In carrying out these objects, the invention is susceptible of a wide range of modification without departing from the spirit or sacrificing any of the advantages of the claimed 25 invention there being shown in the drawings for illustrative purposes a preferred and practical form, in which:

Figure 1 represents a perspective view of 30 one form of manicuring implement embodying this invention;

Fig. 2 is a longitudinal section on an enlarged scale with the barrel broken off for convenience in illustration;

Fig. 3 is a transverse section taken through 35 the tip;

Fig. 4 is a perspective view showing a slightly different form of the invention, and

Fig. 5 is a longitudinal section through the 40 tip and seat member of the form shown in Fig. 4.

One form of the invention is illustrated in Figs. 1 to 3, and a slightly different form in Figs. 4 and 5. In the form shown in Figs. 1 to 3, the implement 1 comprises a barrel or reservoir 2 constructed of any suitable material, and of any desired size, preferably about the size of a large fountain pen barrel, and which is similar in construction to said barrel, being provided at its front end with an internally threaded portion 2^a to receive an exteriorly threaded reduced neck portion 3^a of a cone-shaped closure member 3 preferably constructed of hard rubber and which is designed as a seat or connector for the tip 6. This member 3 has a bore 4 extending longitudinally therethrough enlarged at its outer end as shown at 5 to receive the stem or shank 7 of the tip which fits snugly therein and is held in position by friction. As shown this 60 tip 6 is substantially ovate in form, and has a bore 8 extending longitudinally through the stem 7 and through a portion of the body thereof merging at its front end into a transversely extending bore 9 which opens through 65 one side of the tip as shown in Fig. 2, and in this bore is mounted a plug 11 which forms an abutment for one end of a coiled spring 12, the other end of which bears against a valve 13 which operates normally to close the bore 70 8, the spring 12 holding it in this position. This valve 13 has a reduced stem 14 which extends transversely through the other side of the tip with its end projecting beyond the outer face of said tip and against which 75 end bears a spring 15 here shown in the form of a spring metal strip having one end 16 bent laterally at right angles thereto and embedded in the body of the tip, while the other end thereof rests against the outer face of the 80 connecting member 3. It will thus be seen that a pressure on the spring 15 directly over the stem 14 will operate to move the valve 13 inward against the tension of spring 12 and thus open the bore 8, which has a 85 branch 17 extending through one face of the tip as shown at 18 in Figs. 1 and 3 and through which the liquid is designed to pass and be supplied to the fingernail. This bore 17 has its discharge end 18 located in a 90 nipple-like extension to facilitate the application of the liquid to the fingernail. As shown, this discharge nipple 18 is located at one side of the tip 6 but obviously its location may be varied. The operation of the device 95 it is thought will be obvious, the nipple 18 being placed at the junction of the cuticle and nail while the lever or spring 15 is pressed to open the valve 13 and the device is drawn along the nail at this junction, causing free 100 flow of fluid from the nipple, which may be controlled by varying the pressure on the lever.

It is of course obvious that the barrel 2 may be operated by any desired means, the member 3 being shown removable for this purpose.

In the form shown in Figs. 4 and 5, the barrel 2^b is the same as that shown at 2 in the other figures, and the tip seat 3^b is similar to that 3 of the other figures. The tip 6^a is 110 of substantially the same shape and construction as that shown in the other figures and the

same reference numerals are employed in this form, as in the other except that the exponents "a" are used in connection with them on the parts which correspond to those of the other figures. The only difference in this form is that the spring or lever 15 is omitted and the opening through which the valve stem 14 passes is made larger and operates as the discharge nozzle for the tip.

10 The stem 14^a is provided with a felt covered barrel 20 which forms a closure for the duct 10^a normally and which may be opened by pressing it on the nail or other object forcing the stem 14^a inwardly a sufficient distance to

15 remove the valve 13^a from over the conduit 8^a and permit the liquid of the barrel to flow out. This device 20 also may be used as a medicament applicator, instead of the roll of absorbent cotton usually employed for

20 this purpose.

20 this purpose.
The front end of the tip 6 shown in Figs.
1 to 3 and the same end shown in Figs. 4 and
5 is preferably pointed, as shown at 21, and
21 respectively, and is designed to be used in
25 pushing away the cuticle from the nail in the
same manner that the rosewood or orange-
wood stick is used.

Without further description it is thought that the features and advantages of the invention will be readily apparent to those skilled in the art, and it will of course be understood that changes in the form, proportion and minor details of construction may be resorted to, without departing from the spirit of the invention or its scope as claimed.

I claim:—

1 claim:

1. A manicure implement comprising a reservoir, a tip seat carried by said reservoir, a tip mounted in said seat, said tip and seat having registering bores communicating with the interior of the reservoir, a discharge conduit leading from the bore in said tip, a valve normally closing said conduit, and means operable from the exterior of the tip for opening said valve.

ing said valve.

2. A manicure implement comprising a reservoir, a tip carried by said reservoir and having a bore communicating with the inte-

rior thereof, a discharge conduit leading from said bore, a valve located at the junction of said bore and conduit, a spring normally holding said valve in closed position to shut off the discharge, and means operable from the exterior of the tip to open said valve against the tension of said spring. . . . .

3. A manicure implement comprising a reservoir having an opening therein provided with a cone-shaped closure, an elongated substantially egg-shaped tip carried by said closure, said tip and closure having registering bores communicating with the interior of the reservoir, a bore extending transversely of said tip and communicating with the longitudinal bore therein, a spring pressed valve located in said transverse bore in position to close the longitudinal bore, and a discharge conduit leading from said transverse bore and controllable by said valve to regulate the discharge of fluid from the reservoir. 60 65

4. A manicure implement comprising a barrel closed at one end and open at the other, a cone-shaped closure for said open end removably mounted in said end, a bore extending through the apex of said closure and communicating with the barrel the outer end of said bore being enlarged to form a seat, an ovate tip having a stem detachably and snugly fitting in said seat, a bore extending longitudinally through a portion of said tip and through its stem communicating with the bore in the closure, a discharge conduit communicating with the bore in the tip, a spring pressed valve located to cutoff the passage between the bore and the conduit, a stem carried by said valve projecting through one side of said tip, and a lever for operating said stem to open said valve to discharge liquid when desired.

5. A manicure implement comprising a reservoir, a tip carried by said reservoir having a bore communicating with the interior thereof, a discharge conduit leading from the bore in said tip, a valve normally closing said conduit, and means operable from the exterior of the tip for opening said valve. 90
